Primary Examiner — Gino Colan*(74) Attorney, Agent, or Firm* — Barley Snyder(57) **CLAIM**

The ornamental design for a paver pedestal, as shown and described.

DESCRIPTION

FIG. 1 is a front, top and left side perspective view of a paver pedestal showing our new design;

FIG. 2 is a top perspective view thereof;

FIG. 3 is a top plan view thereof;

FIG. 4 is a front elevation view thereof;

FIG. 5 is a rear elevation view thereof;

FIG. 6 is a bottom plan view thereof;

FIG. 7 is a right side elevation view thereof;

FIG. 8 is a left side elevation view thereof;

FIG. 9 is a front, bottom and left side perspective view thereof; and,

FIG. 10 is a rear, bottom and right side perspective view thereof.

The broken lines shown in the figures are for the purpose of illustrating portions of the paver pedestal and form no part of the claimed design.
